UNITED STATES PATENT OFFICE.

FREDRIK HALVORSEN, OF SEATTLE, WASHINGTON, ASSIGNOR OF ONE-HALF TO
HJALMAR S. HANSON, OF SEATTLE, WASHINGTON.

UNDERCUTTING-SAW GUIDE.

Application filed April 12, 1922. Serial No. 551,966.

To all whom it may concern:

Be it known that I, FREDRIK HALVORSEN, a subject of the Kingdom of Norway, and resident of the city of Seattle, in the county of King and State of Washington, have invented certain new and useful Improvements in Undercutting-Saw Guides, of which the following is a specification.

My invention relates to a device intended to be attached to an axe handle for the purpose of guiding and supporting a saw thereupon in undercutting a log.

All such devices heretofore produced have been useful only when the saw was placed in certain unnatural positions, and useless when in other positions, or else they required considerable adjustment and were of complicated design. It is my object to produce a very simple, light device which will accomplish the desired result, and one which may be attached to the axe while the latter is in its most natural position in the log, being that position best adapted to hold the axe.

It is also my object to produce such a device which will properly guide the saw and support it from the axe handle when the latter is in any one of a number of different positions, all without complicated adjustments.

A still further object is to produce such a device which will have few parts, and will have these so arranged that they cannot be lost off.

My invention comprises those novel parts and combinations thereof which are shown in the accompanying drawings, described in the specification, and particularly defined by the claims terminating the same.

In the accompanying drawings I have shown my invention in the form which is now preferred by me.

Figure 1 is a plan view of a log being undercut, and Figure 2 is a cross-section thereof, showing my device in use.

Figure 3 is a plan view of the device itself, and Figure 4 is an end elevation thereof.

In order to facilitate the movement of the saw over its support, and to guide it, such devices commonly employ a grooved roller, and I have therefor provided the grooved roller 1, this being journaled upon an arm 2. Obviously, as the roller is only used to reduce friction, the arm 1 alone might be employed.

The groove 11 in the roller, or in the arm 2 if the roller is omitted, must lie in a plane which is normal to the axis of the log L being cut, or otherwise the edge of the saw S will bind therein, or be thrown to one side so that the cut will be made at an angle vertically or horizontally, or both.

Such devices are commonly supported upon the handle of an axe driven into the log, to gain the advantage of the spring of the axe handle. I have therefore shown an axe A driven into the log L, its handle extending outwardly and downwardly with respect to the axis of the log L. This is the natural position for such an axe to occupy, when driven in by a right-handed sawyer or "bucker" working from partially beneath the log. Further, such a position of the axe cuts the fibers of the log, and hence it is held most firmly therein.

With former appliances it has not been possible, without complicated adjustment, to employ an axe thus naturally driven into the log, and in the woods heavy, complicated appliances which can be adjusted for such positions cannot be carried about, and parts are liable to be broken or lost, rendering the device useless. I have therefore supported the arm 2 directly in a head 32, from which it projects laterally, the head 32 forming an integral portion of a clevis 3 which is adapted to be clamped upon the handle H. The particular clamping means is unimportant, being shown as the clamping screw 30 having a swiveled handle-engaging tip 31.

In order to correct the outward inclination of the handle H the head 32 is angularly positioned relative to the general plane of the clevis 3; that is, it extends laterally from such plane at about the angle the axe handle H would naturally make with the log axis as seen from above. (See Fig. 1.) In order to correct for the handle's downward inclination, and finally to bring the groove 11 into a plane perpendicular to the log's axis, the arm 2 is extended from the head 32 which supports it at an angle to the general plane of the clevis 3 and its head 32, or inclined towards the opposite end of the clevis. (See Fig. 4.) This inclination would ordinarily be at about the downward angle naturally assumed by the axe handle as seen from the side.

Heretofore I have described the arm 2 as

though it were rigid with the head 32, and it might be so formed. I greatly prefer, however, that the arm be pivoted in the head to swing into other positions corresponding to various positions of the axe handle. The pivot pin 23 extends in the general angular direction of the head 32, and lies in a plane perpendicular to the axis of the log L. Stop surfaces 21 upon the arm 2 engage cooperating surfaces 33 upon the head 32, to correctly position the arm in either extreme position.

The axe may be driven into the log so that its handle extends upwardly and outwardly. It is then only necessary to apply the clevis with its opening outward from, instead of towards, the log, the arm 2 remaining in the same position. This brings the groove 11 into the proper plane. If the 20 axe is driven in left-handedly, and extending downward, the opening of the clevis remains towards the log, but the arm 2 is thrown over into its other extreme position, again bringing the groove 11 into the 25 proper plane. Variations in the outward inclination of the axe can be compensated for by turning the clevis about the axis of the clamping screw 30.

What I claim as my invention is:

1. An undercutting-saw guide comprising a clevis adapted to be secured to an axe handle, an integral head angularly positioned with respect to the general plane of the clevis, and a guiding and supporting arm carried by said head.

2. An undercutting-saw guide comprising a clevis adapted to be secured to an axe handle, a head extending laterally at an angle from the general plane of the clevis, and a guiding and supporting arm extending laterally from said head and inclined towards the opposite end of the clevis.

3. An undercutting-saw guide comprising a clevis adapted to be secured to an axe handle, a head extending laterally at an angle from the general plane of the clevis at

one end thereof, a guiding and supporting arm pivoted in said head to lie upon either side of the clevis, and a stop surface upon the head to position said arm inclined downwardly towards the opposite end of the clevis upon either side thereof.

4. An undercutting-saw guide comprising a clevis adapted to be secured to an axe handle, a head upon one end of the clevis and extending at an angle to the general plane thereof, a guiding and supporting arm pivoted upon said head, its pivot axis extending in the same angular direction as the head, cooperating stops upon said arm and head whereby said arm may be positioned in two extreme positions removed more than 180° from each other at opposite sides of the plane of the clevis, and a grooved roller journaled upon said arm.

5. In an undercutting-saw guide, the combination with a guiding and supporting arm adapted to extend substantially parallel with the axis of the log to be cut, of a clevis adapted to be secured upon an axe handle extending downwardly and outwardly with respect to the log axis, and a head integral with said clevis and angularly positioned relative to its general plane, and forming a support for said arm.

6. In an undercutting-saw guide, the combination with a guiding and supporting arm adapted to extend substantially parallel with the axis of the log to be cut, of a clevis adapted to be secured upon an axe handle which extends downwardly and outwardly with respect to the log axis, and a head integral with said clevis and having a pivotal support for an end of said arm adapting it to be swung to another position about the head, the axis of said pivot extending at an angle to the general plane of the clevis and lying in a plane substantially normal to the log axis.

Signed at Seattle, King County, Washington, this 6th day of April, 1922.

FREDRIK HALVORSEN.
